UNITED STATES PATENT OFFICE.

WILLIAM E. WILLIAMS, OF HARRISONVILLE, MISSOURI, ASSIGNOR OF ONE-FOURTH
TO J. H. BOWMAN, OF HARRISONVILLE, MISSOURI.

END GATE.

Application filed May 26, 1928. Serial No. 280,885.

This invention relates to an endgate designed primarily for use in connection with vehicle bodies such as used for hauling grain and the like.

5 One of the objects is to provide an endgate which can be supported in any one of four positions, namely, closed position, dumping position, scooping position, and in position as a rearward extension of the floor of the 10 vehicle body.

Another object is to provide simple and efficient means for holding the endgate in any one of the positions mentioned.

With the foregoing and other objects in view which will appear as the description proceeds the invention resides in the combination and arrangement of parts and in the details of construction hereinafter described and claimed it being understood that changes 20 in the precise embodiment of the invention herein disclosed may be made within the scope of what is claimed without departing from the spirit of the invention.

In the accompanying drawings the preferred form of the invention has been shown.

In said drawings,

Figure 1 is a side elevation of the endgate and a portion of the vehicle body, said endgate being shown, by full lines, in position for 30 use as an extension of the bottom of the vehicle body and, by broken lines, in position for use as a scoop.

Figure 2 is a side elevation showing the opposite side of the endgate and adjacent portion of the body, said endgate being shown by full lines in closed position and, by broken lines, in dumping position.

Figure 3 is a rear elevation of the endgate.

Figure 4 is a section on line 4—4, Figure 2, 40 said section being through one side portion of the endgate.

Figure 5 is a section through a portion of the endgate taken on the line 5—5, Figure 3, showing one of the locking bolts in plan.

45 Figure 6 is a section on line 6—6, Figure 3.

Figure 7 is a section on line 7—7, Figure 2.

Figure 8 is a rear elevation of the lower portion of one side of the endgate while in closed position, the adjacent portion of the vehicle body being shown in section.

50 Figure 9 is a rear elevation of the latch disk, adjacent parts being shown and the handle being in dotted lines.

Referring to the figures by characters of 55 reference 1 designates the rear portion of the

body of a vehicle reinforced across the back thereof with a transversely extended angle strip 2 provided, at its ends, with upturned ears 3. Each of these ears is recessed as at 4 so as to provide a hook. Secured to each side 60 of the vehicle body 1 near the rear end of the lower portion thereof is a bracket 5 having an outstanding ear 6 the upper edge of which is formed with an angular notch 7 shown particularly in Figure 8. Adjacent the top 65 of the vehicle body near the rear end thereof is secured a plate 8 having a laterally extending flange 9. The plate 8 has an angle strip 10 riveted or otherwise fastened to the bottom of its flange 9 and pivotally connected to the 70 rear portion of this angle strip is a link 11 having a flange 12. The pivot of this link has been shown at 13. The flange 12 of the link 11 is adapted to be normally held against the flange 9 by a bolt 14 as shown by broken 75 lines in Figure 1 and by full lines in Figure 7.

The endgate 15 includes the bottom portion 16 reinforced by cross strips 17 and is provided with side boards 18 fixed relative to the bottom 16 and spaced apart a sufficient distance 80 to receive between them the rear end of the body 1 when the endgate is in upstanding position as shown in Figure 2. The outer sides of the side boards 18 are lapped by movable side boards 19 pivotally connected 85 to the side boards 18 at their forward ends as shown at 20. Elongated guide loops 21 are carried by the side boards 18 and are supported at the outer sides thereof, these loops being parallel with the sides of the 90 boards 18 and constituting guides for the movable side boards 19. In this connection attention is directed to Figure 4 of the drawings.

Secured to the sides of the bottom 16 of the 95 endgate at that end thereof nearest the bottom of the vehicle body are sleeves 22. Each of these sleeves has a bolt 23 mounted for rotation therein. One end of the bolt has a radial lug 24 adapted to engage in the recessed or hooked ear 3 as shown in Figures 1 and 2. An arm 25 is extended from the other end of the bolt.

Mounted on the cross strip 17 nearest the bottom of the body 1 is a bracket 27 having an 100 upwardly extended flange 28 on which a disk 29 is pivotally mounted. Links 26 are pivotally connected to the disk 29 at diametrically opposed points and to this disk is also connected a suitable handle 30 whereby the disk can be 110

rotated readily. The disk has a notch 31 in its periphery for the reception of a latch 32 pivotally mounted on the bracket 27 and held normally pressed against the disk by a spring 32'. This latch is adapted to be seated in the notch when the lugs 24 are extended laterally and seated in the ears 3 as shown in Figure 3.

When the endgate is in upstanding or closed position the movable side boards 19 completely lap the side boards 18. Tongues 33 are extended from the side boards 19 close to their lower ends (while the side boards are in upstanding positions as in Figure 2) and each of these tongues has an angular recess 34 adapted to receive the ear 6, the upper end portion of the recess being adapted to receive the bottom portion of the adjacent notch or recess 7 in the ear 6. The inclined walls of the notches or recesses 7 and 34 cooperate to hold the parts against relative swinging movement while they are in interfitting relation.

Links 35 are pivotally connected to the respective movable side boards and each of these links 35 is connected by an intermediate link 36 to one of the links 11. Each link 35 has one end portion offset as shown at 37 to provide a projecting tongue and the links 36 also have an extending portion 38 formed with a laterally extended flange 39. When the endgate is in upstanding or closed position as shown by full lines in Figure 2, the links 35 will be extended upwardly while the links 36 will be extended rearwardly. At this time the links 11 are held in forwardly extended positions with their flanges 12 clamped against the flanges 9 of the plates 8. With the several links thus located the links 35 will thrust rearwardly against the flanges 39 which thus act as a reinforcement for the pivot pins 40 which connect the links 35 and 36 this being apparent by referring to Figure 2.

A latch 41 is pivotally connected to each of the movable side boards 19, each latch having a flange 42 provided with a slot 43. When the links are located as in Figure 2 the upper offset portions 37 of the links 35 will be extended into the slots 43 in the flanges 42 so that the parts will thus be held positively against relative movement.

Under normal conditions the endgate is mounted as shown in Figure 2 and, obviously, will be held against movement relative to the vehicle body. When it is desired to dump material by shifting the endgate to the position indicated by broken lines in Figure 2, the latch 32 is disengaged from the disk 29 and said disk is rotated by means of the handle 30. Thus motion will be transmitted from the disk through the links 26 to the arms 25 and the bolts 23 will be rotated to swing the lugs 24 out of the recesses 24 in the ears 3.

The operation just described uncouples the bottom 16 and side boards 18 from the vehicle body although the side boards 19 remain fixed relative thereto because the tongues 33 remain

in engagement with the ears 6. When the parts are thus released the bottom 16 and side boards 18 of the endgate can swing rearwardly about their pivots 20 thereby releasing bulk material so it can be delivered downwardly 70 between the bottom of the endgate and the bottom of the vehicle body. Following this operation the endgate can be swung to closed position, disk 29 can be rotated to rotate the bolts and swing the lugs 24 into the recesses 4 75 and the latch 32 will snap into the notch 31, thereby holding the parts again in the position shown by full lines in Figure 2.

When it is desired to use the endgate as a scoop the bolts 23 and their lugs 24 are not disturbed. Instead the latches 41 are swung upwardly so as to disengage their flanges 42 from the offset ends of the links 35. The endgate is thus free to swing downwardly, the lugs 24 acting as pivots and the tongues 33 85 on the movable side boards 19 lifting off of the ears 6 as shown by broken lines in Figure 1. When it is desired to extend the bottom of the endgate rearwardly in the same plane as the bottom of the vehicle, as shown by full lines 90 in Figure 1, the links 11 are released by detaching the bolts 14. Said links 11 will then swing rearwardly so as to permit the endgate to move downwardly to the full line position shown in Figure 1, the movement of the side 95 boards 19 relative to the side boards 18 being limited by the guides 21.

What is claimed is:

1. The combination with a vehicle body, of an endgate including pivotally connected 100 fixed and movable side boards, a detachable pivotal connection between the bottom of the endgate and the bottom of the vehicle body, a flexible connection between the movable side boards and the vehicle body, cooperating means on the body and the movable side boards for supporting said side boards in upstanding positions when the endgate is closed, and means for fastening the endgate in upstanding position.

2. The combination with a vehicle body, of an endgate including pivotally connected 110 fixed and movable side boards and a bottom connecting the fixed side boards, cooperating means on the vehicle body and the movable side boards for supporting the movable side boards, means for holding the movable side boards in upstanding positions, and cooperating means on the vehicle body and the bottom of the endgate for holding the fixed side 115 boards and the bottom connecting them against movement relative to the body, said supported movable side boards constituting supports for the fixed side boards and the connecting bottom when disengaged from 120 the vehicle body.

3. The combination with a vehicle body, of side boards, separable cooperating means on the body and side boards for detachably supporting said side boards in upstanding 130

positions, an endgate bottom having side boards fixed relative thereto pivotally connected to and adapted to be supported by the first named side boards, cooperating means 5 upon the vehicle body and the bottom of the endgate for supporting said bottom of the endgate for swinging movement independently of the first named side boards, and flexible means connecting the vehicle body 10 and the first named side boards for controlling the swinging movement of the bottom of the endgate.

4. An end gate including pivotally connected side boards arranged in pairs, a bottom connecting the side boards of one pair, means for detachably and pivotally connecting said bottom to a vehicle body, and adjustable means for supporting one pair of side boards in upstanding positions fixed 20 relative to the body to support the bottom of the endgate when detached from the body.

5. The combination with a vehicle body, of an endgate pivotally and detachably connected thereto, side boards pivotally connected 25 at one end to the endgate, means for supporting the side boards in upstanding positions at the sides of the body, foldable means connecting the side boards to the body for supporting the side boards and the endgate 30 in rearwardly extended positions, said foldable means being adjustable to support the

endgate at different angles relative to the body, means on the side boards cooperating with the foldable means for holding said side boards in upstanding positions to constitute supports for the endgate when detached from the body, and means on the endgate for limiting the swinging movement of the endgate and side boards relative to each other. 35

6. The combination with a vehicle body, of an endgate, side boards pivotally connected to the endgate and extending along the sides thereof, means for detachably supporting the side boards from the sides of the vehicle body, a foldable link connection between each side board and one side of the vehicle body, a latch carried by each side board for engagement with one of the links to hold the link against relative movement and maintain 40 the side board in upstanding position relative to the body, means for detachably connecting one end portion of the endgate to the sides of the body for controlling the movement of the endgate relative to the 45 side boards, and means carried by the endgate and cooperating with the side boards for limiting the relative movement of the endgate. 50

In testimony that I claim the foregoing as 55 my own, I have hereto affixed my signature.

WILLIAM E. WILLIAMS.
